(57) **CLAIM**

The ornamental design for a fabric care appliance as shown and described.

DESCRIPTION

FIG. 1 is a perspective view of a fabric care appliance according to the claimed design in a first configuration; FIG. 2 is a front elevation view thereof; FIG. 3 is a back elevation view thereof; FIG. 4 is a right side elevation view thereof; FIG. 5 is a left side elevation view thereof; FIG. 6 is a top plan view thereof; FIG. 7 is a bottom plan view thereof; FIG. 8 is a top plan view thereof with the portion of the article above the line 8-8 in FIG. 4 removed; FIG. 9 is a perspective view of the fabric care appliance according to the claimed design in a second configuration; FIG. 10 is a front elevation view thereof, a back elevation view being identical to the view shown in FIG. 3; FIG. 11 is a right side elevation view thereof; FIG. 12 is a left side elevation view thereof; FIG. 13 is a top plan view thereof, a back elevation view being identical to the view shown in FIG. 7; and, FIG. 14 is a top plan view thereof with the portion of the article above the line 14-14 in FIG. 12 removed. The portions of the article shown in even broken line form no part of the claimed design.

(Continued)

Dash-dot-dash broken lines between shaded and un-shaded areas represent bounds of the claimed design and form no part of the claimed design themselves.

1 Claim, 12 Drawing Sheets

Related U.S. Application Data

a division of application No. 29/610,407, filed on Jul. 12, 2017, now Pat. No. Des. 878,686.
